UNITED STATES PATENT OFFICE.

JAMES R. FLOYD, OF NEW YORK, N. Y.

APPARATUS FOR ELEVATING THE COVERS OF GAS-PURIFIERS.

SPECIFICATION forming part of Letters Patent No. 396,332, dated January 15, 1889.

Application filed June 2, 1888. Serial No. 275,811. (No model.)

To all whom it may concern:

Be it known that I, JAMES R. FLOYD, of the city, county, and State of New York, a citizen of the United States, have invented certain 5 Improvements in Apparatus for Elevating the Covers of Gas-Purifiers, of which the following is a full, clear, and exact description, reference being had to the accompanying drawings, forming part of this specification.

10 My invention relates to an apparatus for raising the cover of a gas-purifier by hydraulic power, in which a cylinder mounted on the cover-carriage has the rod of its piston connected to the cover, and a pump is

15 provided for forcing fluid under pressure into the cylinder to raise the piston, and hence elevate the cover on the carriage; and my invention consists in the combination, in said apparatus, with several cylinders therein and

20 a force-pump common to all said cylinders, of the hereinafter-described conduits connecting the pump and the cylinders and the valves therein intermediate said pump and cylinders, whereby a uniform pressure of the fluid

25 may be maintained in each of the several cylinders, for the purpose hereinafter set forth.

Figure 1 is an elevation in perspective of a gas-purifier, its cover, and the carriage thereof containing my invention. Fig. 2 is a vertical section of one of the cylinders, and Fig. 3 is a plan of the cylinders and pump and the system of fluid conduits and their valves containing my invention.

A is the gas-purifier. A' is the cover thereof.

BB'B'B³ represent several cylinders mounted on the frame of the carriage B⁴ and usually one at each of the four corners thereof. These cylinders may be made or provided 40 with a wide external flange, b, by which they may be conveniently mounted on the carriage. Each cylinder has a piston, b', the rod b² of which is connected to the cover A', usually one to each corner, as shown.

45 C is a pump for forcing fluid to the several cylinders B, the fluid entering by suitable connections at the lower end of the cylinder below the piston, as shown at c, Fig. 2.

50 My present improvement consists in the combination, with the several cylinders and the pump, in the structure constructed sub-

stantially as above described, of pipes or fluid-conduits leading from the force-pump to each of the cylinders, together with valves located in said piping or conduits, one intermediate each cylinder individually and said pump, whereby a uniform or equal force of the liquid driven by the pump may be exerted upon the piston in each of the several cylinders.

55 At D D' D² D³ are shown pipes leading to each of the several cylinders B B' B² B³, said cylinders being shown as four in number in the drawings. These pipes are conveniently placed along the longitudinal sides of the 60 frame B⁴ of the carriage, leading toward each other on the respective sides from the opposite corners, as shown.

65 At E is shown piping leading from the pump to the several pipes D D' D² D³, this piping consisting, preferably, of sections e e', leading from the opposed ends of both the pipes D D³ and D' D², respectively, on the opposite sides of the carriage and extending to about the center of the carriage-frame, 70 where they are united to a section, e², connecting with the pump, as shown. A stand-pipe, e³, into which the several sections e e' e² open, is preferably provided at the junction of said sections at the center of the carriage-frame, as shown.

75 At d d' d² d³ are shown valves located one in each of the several pipes D D' D² D³, respectively, between the cylinder, to which each said pipe communicates, and the junction of each said pipe with the piping leading to the pump, as shown. For conveniently operating these valves individually each valve may be provided with a rod, d⁴, and all the 80 said rods may lead to that side of the carriage-frame on which the pump C is located, where each may be provided with an operating-lever, d⁵, fulcrumed or pivoted on the carriage-frame, as shown.

85 The object of my described improvement is to enable the cover of the purifier to be raised by the pistons of the several cylinders uniformly at the several points of connection of the piston-rods to the cover, and thus to avoid the tilting of the cover, and hence 90 the binding of its edges or edge-flanges against the walls of the purifier around its

top, as has been found to occur in the elevating apparatus as heretofore constructed, in which the fluid-conduits leading from the pump to the several cylinders have been given 5 a permanently-uniform capacity or area of discharge into each cylinder. When thus constructed, the greatest pressure has been exerted by the fluid upon the pistons of the cylinders nearest to the pump, and hence these 10 pistons have been forced upward in advance of those of the remaining cylinders, causing the heavy cover to jam or bind, by its tilting, in the mouth of the purifier, and necessitating the use of great force to liberate it, there- 15 by entailing serious delay in the operation of the apparatus.

It is evident that by means of my described improvement the workman operating the pump may readily control the force applied 20 to each piston of the several cylinders, so that the cover will rise from the purifier at a uniform rate at all points of its connection to the several pistons.

My further improvement consists in a cap 25 or head, F, arranged to close the upper end of each cylinder, said cap having an aperture, f, to which on each cylinder is connected a pipe, f', leading to a tank, f², which is conveniently mounted on the carriage-frame, as 30 shown, and preferably near the pump. The leakage of the water or other fluid around each piston into the upper end of the cylinders will by this means be discharged into the tank, and its overflow from and dripping over 35 and upon the exterior of the cylinder, and consequent liability to rust the cylinder and the carriage-frame, as occurs when the cylinders are wholly open at the top, are obviated, and cleanliness and durability in the apparatus 40 are promoted.

The tank f² is desirably connected to the pump C, so that it will serve as a reservoir for the fluid used by the pump to operate the cylinder-pistons. This connection is shown 45 at f³, the fluid returning to the tank through the pump and this connection, when the cover is allowed to fall to its place in the purifier, thus promoting economy in the operation of the apparatus.

50 What I claim as my invention, and desire to secure by Letters Patent, is—

1. In an apparatus for elevating the cover of a gas-purifier, the combination, with the several described cylinders connected to the carriage B⁴ and having the rods of their several pistons attached to the purifier-cover at various points thereon, respectively, together with a pump, C, for operating said pistons, of the described pipes severally connecting said pump with said cylinders, valves in said pipes 55 located, one in each, intermediate said pump and said cylinders, and rods for operating said valves individually, substantially as and for the purpose set forth.

2. In an apparatus for elevating the cover 60 of a gas-purifier, the combination, with several cylinders mounted on the cover-carriage and having the rods of their several pistons attached, respectively, to the corners of the purifier-cover, together with a pump for operating said pistons mounted on said carriage, of pipes extending longitudinally of the carriage and connected, respectively, to said cylinders and to pipe-sections extending laterally of the carriage, a stand-pipe uniting said 75 lateral pipe-sections, a pipe connecting said stand-pipe and the pump, and valves, located one in each of the longitudinal pipes, having rods reaching to and provided individually with operating-levers on that side of the carriage-frame on which the said pump is located, all substantially as and for the purpose set forth.

3. In an apparatus for elevating the cover 80 of a gas-purifier, the combination, with several cylinders mounted on the cover-carriage and having the rods of their several pistons attached, respectively, to the purifier-cover at the corners thereof, together with a pump for operating said pistons, of a tank mounted on 85 said carriage and having connection with said pump, and pipes leading severally from an aperture in the upper head of each cylinder to said tank, substantially as described, and for the purpose set forth.

JAMES R. FLOYD.
